Patented May 23, 1916.

Inventor

UNITED STATES PATENT OFFICE.

CHARLES KERR, OF GREEN BAY, WISCONSIN.

DESIGN FOR A HAT-PIN OR SIMILAR ARTICLE.

49,092.

Specification for Design.

Patented May 23, 1916.

Application filed January 28, 1916. Serial No. 74,885. Term of patent 3½ years.

To all whom it may concern:

Be it known that I, CHARLES KERR, a citizen of the United States, residing at Green Bay, in the county of Brown and State of Wisconsin, have invented a new, original, and ornamental Design for a Hat-Pin or Similar Article, of which the following is a specification, reference being had to the accompanying drawing, forming part thereof.

The figure is a plan view of a hat pin, showing my new design.

I claim:

The ornamental design for a hat pin or similar article, as shown.

CHAS. KERR.

Witnesses:

H. F. CAMM,
J. T. WHITMACK.
